WAVE-SIGNAL TRANSLATING SYSTEM

Bernard D. Loughlin, Bayside, N. Y., assignor, by
mesne assignments, to Hazeltine Research,
Inc., Chicago, Ill., a corporation of Illinois

Application December 31, 1943, Serial No. 516,394

7 Claims. (Cl. 177—353)

1

This invention relates, in general, to wave-signal translating systems and is particularly directed to coding or secrecy aspects of transponder systems. As used throughout this specification and in the appended claims, the term "transponder system" is intended to describe a wave-signal translating system which includes a receiving system and a transmitting system so arranged that a predetermined answer or reply signal is transmitted in response to a received interrogating signal, the reply and interrogating signals preferably comprising radiant-energy wave signals.

Transponder systems of the type under consideration are frequently utilized as beacons for supplying direction-finding information to air traffic. In the usual installation the system is designed to translate pulse-modulated wave signals in a pulse-by-pulse fashion. That is, the receiving system is designed to receive a radiated interrogating signal having pulse-type characteristic variations, such as pulse-type amplitude variations, and the transmitting system is designed to transmit a reply signal having similar characteristic variations, their operation being such that each modulation pulse of the received interrogating signal causes the transmission of a single pulse of the reply signal. While transponder systems of the prior art have proved to be generally satisfactory, it may be desirable in particular installations to render the system secret and thus preclude unauthorized listeners from deriving useful information. The required secrecy may be obtained through the use of a transponder system having a receiver portion which responds only to received interrogating signals which are coded in accordance with a prescribed coding schedule. The prior art systems mentioned, arranged for a pulse-by-pulse response to received signals, do not lend themselves particularly well to such installations.

It is an object of the invention, therefore, to provide an improved wave-signal transponder system which substantially avoids the above-mentioned limitation of prior art arrangements.

It is a further object of the invention to provide an improved transponder system for transmitting a reply signal, which may or may not be coded, in response to an interrogating signal having a plurality of pulse-type characteristic variations of predetermined pulse durations occurring in a predetermined time sequence.

It is a further object of the invention to provide a wave-signal transponder system which includes

2

improved coding arrangements in its receiving system.

It is a still further object of the invention to provide a wave-signal transponder system having an improved signal-to-noise ratio.

In accordance with the invention, a selective wave-signal translating system for translating a signal having a plurality of pulse-type amplitude variations of predetermined pulse durations occurring in a predetermined time sequence comprises an input circuit for receiving the signal. Means are coupled to the input circuit for deriving from the received signal a first corresponding plurality of signal impulses occurring in time coincidence and individually representing the leading edge of a different one of said pulse-type amplitude variations of the received signal. Means are also provided for deriving from the received signal a second corresponding plurality of signal impulses occurring in time coincidence with one another and with the first-mentioned plurality of signal impulses and individually representing the trailing edge of a different one of the pulse-type variations of the received signal. Finally, the system has means responsive jointly to the coincident first and second plurality of signal impulses for deriving an output signal, whereby the translating system is responsive only to signals having pulse-type amplitude variations of the aforesaid predetermined durations and occurring in the aforesaid predetermined time sequence.

For a better understanding of the present invention, together with other and further objects thereof, reference is had to the following description taken in connection with the accompanying drawings, and its scope will be pointed out in the appended claims.

Fig. 1 of the drawings is a schematic circuit diagram of a wave-signal transponder system having a selective receiver system; Figs. 2 and 3 comprise graphs utilized in explaining the operation of the arrangement of Fig. 1; Fig. 4 represents a portion of the Fig. 1 arrangement modified to include the present invention; Fig. 5 comprises a set of graphs utilized in explaining the operation of the Fig. 4 arrangement; Fig. 6 represents in modified form a further portion of the Fig. 1 arrangement; and Fig. 7 comprises a set of 50 graphs used in explaining the operation of the arrangement of Fig. 6.

Referring now more particularly to the drawings, there is represented in Fig. 1 a wave-signal transponder system having coding devices contributing desired secrecy features. For conven-

ience of explanation, the system may be considered as a radio beacon adapted to transmit direction-finding information to interrogating aircraft. As represented, the radio beacon includes a selective receiving system in accordance with the present invention having an antenna system 10, 11 coupled to a carrier-frequency signal translator or receiver 12. Where the receiver is of the superheterodyne type, the conventional frequency changer, intermediate-frequency amplifiers, band-pass selectors, and signal detector are included in unit 12. Coupled in cascade to receiver 12 are an amplitude limiter 13, a delay-network unit 20 to be described more particularly hereinafter, a clipping amplifier 14, and a keyed multivibrator 15. The band-pass selectors of receiver 12 and the amplitude limiter 13, are arranged, respectively, to limit the frequency components and amplitude of the signal applied to unit 20 in order that this signal may have a predetermined wave form, that is, a predetermined maximum amplitude and predetermined slopes at the leading and trailing edges of its pulse-type amplitude variations. The beacon further includes a transmitting system which forms the subject matter of a divisional application Serial No. 557,953, filed October 10, 1944, now Patent 2,415,359, dated February 4, 1947, in the name of Bernard D. Loughlin and assigned to the same assignee as the present invention. This transmitting system is coupled to the output circuit of multivibrator 15 and consists of a delay-network unit 40, described more particularly hereinafter, an amplifier 16, a carrier-frequency signal generator and modulator or transmitter 17, and a transmitting antenna 18, 19. Transmitter 17 is normally in a quiescent condition but is energized in response to control signals translated through amplifier 16. Elements 10-19, inclusive, may be of any conventional construction and operation. By way of illustration, amplitude limiter 13 may be similar to the limiter arrangement designated 15 of United States Letters Patent 2,271,203, granted January 27, 1942, in the name of Jasper J. Okrent and assigned to the same assignee as the present invention. Clipping amplifier 14 may constitute an amplifier biased to pass only signal components having an amplitude value exceeding a critical level, as illustrated at page 372, Fig. 217B of "Principles of Television Engineering," by Donald G. Fink, published in 1940 by McGraw-Hill Book Company, Inc. Multivibrator 15 may be a trigger circuit of the type shown at page 176, Figs. 4-9 of "Ultra-High-Frequency Techniques," by J. G. Brainerd et al., published in 1942 by D. Van Nostrand Company, Inc.

Neglecting for a moment units 20 and 40 and considering element 14 to be a conventional amplifier, it will be readily apparent to those skilled in the art that the arrangement of Fig. 1 comprises a conventional radio beacon, that is, a signaling system having a receiver and transmitter interconnected so that the output signal of the receiver controls the transmitter to transmit a related signal. Since the operation of such apparatus is generally well understood, a detailed description and explanation thereof is unnecessary. Briefly, however, an aircraft desiring to obtain information from the beacon sends out an interrogating signal having pulse-type amplitude variations of equal pulse durations and equal pulse spacings. This signal is intercepted by antenna system 10, 11 and translated by receiver 12, the modulation components of the signal appearing in the output circuit thereof as a unidirectional

signal having amplitude variations corresponding to those of the received signal. This signal is applied by way of elements 13 and 14 to keyed multivibrator 15, which generates a single control pulse of rectangular wave form and of any desired pulse duration as determined by the circuit parameters of the multivibrator, one such control pulse being generated thereby in response to each modulation pulse of the interrogating signal. The control pulses from multivibrator 15 are translated through amplifier 16, thereby to control transmitter 17 to transmit in response to each such control pulse a single pulse of an answer or reply signal, the transmitted pulses having substantially the same pulse duration, spacings and wave form as those translated through amplifier 16. Thus, the described transponder system, when interrogated by an inquiring aircraft, transmits a reply signal having pulse-type amplitude variations which individually correspond to modulation pulses of the interrogating signal. Expressed differently, the beacon functions in a pulse-by-pulse fashion to transmit an answer in response to an interrogating signal.

Referring now more particularly to the delay-network units 20 and 40 of the Fig. 1 arrangement, these units are associated, respectively, with the receiver and transmitter portions of the transponder system, being provided to afford the desired secrecy characteristics. Unit 20 is a transversal time-delay filter network having input terminals 21, 21 and output terminals 22, 22. The delay network comprises a transmission line consisting of a pair of spaced parallel conductors 23, 23, coupled at one end to input terminals 21, 21, and terminated at the opposite end in the surge or characteristic impedance of the line designated 24. The electrical characteristics of transmission line 23, 23, are preferably such as to effect a uniform predetermined time delay per unit of line length to a signal translated thereby. The physical length of the line is determined by the degree of secrecy desired, as will presently be explained. A plurality of adjustable taps are associated with the line so as to be freely movable therealong, three such taps 25, 26 and 27 being shown in the drawings. Each of taps 25, 26 and 27 is included in circuit with an individual one of isolating resistors 28, 29 and 30 and a common impedance 31. Unit 20 is coupled between output terminals 22, 22, of unit 28. Each isolating resistor has a relatively high impedance as compared with that of common impedance 31.

Unit 40 likewise comprises a transversal time-delay filter network having input terminals 41, 41, output terminals 42, 42, a parallel-conductor transmission line 43, 43, coupled at one end to terminals 41, 41 and terminated at the opposite end in its surge or characteristic impedance 44. Unit 40 also includes a plurality of adjustable taps 45, 46 and 47 adjustably connected to transmission line 43, 43, isolating resistors 48, 49 and 50 individually in circuit with each of the taps, and a common output impedance 51 having a low value of impedance in comparison with that of the individual isolating resistors. Impedance 51 of this arrangement is coupled between the output terminals 42, 42.

In considering the effect of units 20 and 40 on the described operation of the transponder system of Fig. 1, it will be assumed initially that only a single tap is effective in each of such units, namely, tap 25 of unit 20 and tap 45 of unit 40.

It will be further assumed that these taps are positioned adjacent to the input terminals of their respective units, as illustrated. For the assumed condition, a received interrogating signal is translated directly from wave-signal translator 12 through unit 13, tap 25 of unit 20 and amplifier 14 to multivibrator 15. Also, the control pulses generated in multivibrator 15 are translated directly therefrom through tap 45 of unit 40 to amplifier 16 and transmitter 17. Accordingly, for these conditions the operation of the transponder system is substantially as described above.

Now it will be assumed that all of the taps of units 20 and 40 are effective and that such taps are positioned along their associated transmission lines in the manner indicated in the drawings. It will be further assumed that clipping amplifier 14 is adjusted to have a clipping level indicated by broken-line curve c of Fig. 2 and that the interrogating signal as applied to input terminals 21, 21, of unit 20 has the wave form represented by curve e_{25} of Fig. 2. From this last-mentioned curve, it will appear that the interrogating signal as applied to terminals 21, 21, has a maximum amplitude limited to a predetermined value e by unit 13 and a group of three pulse-type amplitude variations of equal pulse durations t occurring in a predetermined time sequence represented by the unequal pulse spacings t_1 and t_2 . It will be understood that the interrogating signal may comprise repeating groups of pulse-type amplitude variations individually having pulse durations and spacings as described and a time separation which is long with reference to the period of a single group. For convenience of explanation, however, the interrogating signal will be considered as consisting of but a single group of such amplitude variations.

The response of the transponder system to such a received signal is illustrated by the curves of Figs. 2 and 3 in which the subscripts indicate the elements where the represented signal voltages are derived. Signal voltages are derived at each of taps 25, 26 and 27. If the signal attenuation along line 23, 23 be neglected, the derived signal voltages individually have a predetermined maximum amplitude equal to the above-mentioned value e and pulse-type amplitude variations corresponding to the modulation of the received interrogating signal. Due to the time-delay characteristics of transmission line 23, 23, and the relative spacings of the adjustable taps, these signal voltages have a time relation with reference to each other such that predetermined amplitude variations of the several signal voltages occur substantially in time-phase relation. More specifically, the third amplitude variation of signal e_{25} , the second amplitude variation of signal e_{26} , and the first amplitude variation of signal e_{27} occur in time-phase relation. These signals add up across load impedance 31, producing an output signal at terminals 22, 22, as represented by curve e_{22} , having one amplitude variation or pulse of such magnitude as to exceed the clipping level c of clipping amplifier 14. This amplitude variation of the output signal corresponds in time with the above-described in-phase components of the individual signals obtained at taps 25, 26 and 27 and produces a control effect which keys multivibrator 15. The multivibrator generates and applies to input terminals 41, 41, of unit 40 a single unidirectional pulse of substantially re-

tangular wave form. The time-delay characteristics of transmission line 43, 43, cause taps 46, 46 and 47 to derive a plurality of signals individually having a wave form corresponding to that of the applied pulse and a time relation with reference to each other such that the signals derived at the individual tapping points appear in a predetermined time sequence. These signals develop across the common impedance 51 a control signal, represented by curve e_{42} of Fig. 3, for application to amplifier 16. This control signal likewise has pulse-type amplitude variations of equal pulse durations t determined by the period of multivibrator 15 and unequal pulse spacings t_5 and t_6 determined by the relative positions of taps 46, 46 and 47. The reply signal transmitted from antenna system 18, 19 in response to this control signal is a pulse-modulated signal comprising components having pulse durations and pulse spacings corresponding to those of control signal e_{42} . In other words, the transponder system including units 20 and 40 with taps arranged as indicated in the drawings responds to interrogating signals having pulse-type amplitude variations occurring in the order mentioned and transmits in reply thereto a complete coded answer, coded in accordance with the relative settings of the taps included in unit 40.

From the foregoing description, it will be apparent that the arrangement of Fig. 1 comprises a wave-signal transponder system for transmitting a coded reply signal in response to an interrogating signal having characteristic variations appearing in a predetermined time sequence. Unit 20 comprises means for deriving from the interrogating signal a plurality of signals individually having characteristic variations determined by predetermined ones of the characteristic variations of the interrogating signal and a time relation with reference to each other such that predetermined variations of the individual characteristics of the plurality of signals occur substantially in time-phase relation. Clipping amplifier 14 and the succeeding units in the system constitute amplitude-selective means responsive jointly to the aforesaid predetermined variations of the plurality of signals for transmitting a coded reply signal.

With reference to the particular coded reply-signal transmitted, unit 40 comprises means for deriving from the interrogating signal a plurality of signals individually having predetermined characteristic variations and a time relation with reference to each other such that predetermined variations of the individual characteristics of the plurality of signals appear in a predetermined time sequence, which may be the same or different from the time sequence of the characteristic variations of the interrogating signal. Furthermore, amplifier 16 and wave-signal generator and modulator 17 comprise means responsive to the predetermined variations of this plurality of signals for transmitting a coded reply signal having components corresponding in number to this plurality of signals and a spacing determined by the time sequence of such plurality of signals.

The coding provisions of the receiver and the transmitter of the described transponder system are helpful in establishing the desired secrecy characteristics and for many installations are adequate. However, it will be noted that while the selective receiver is arranged to respond primarily to interrogating signals having characteristic variations appearing in a predetermined

time sequence, an interrogating signal having an exceedingly long pulse duration such as to include a substantial portion of the period of the time sequence may, in some instances, cause the transponder to reply. This operation may be avoided by the arrangement of Fig. 4 which represents a modification of unit 20, the arrangement being designated generally as 20' and including the present invention.

Unit 20' includes a conventional differentiating circuit 53, and may be of the type illustrated at page 162, Fig. 94 of "Principles of Television Engineering," supra. It is connected between the input terminals 32, 32, of unit 20' and the input terminals 54, 54, of a transversal time-delay filter network comprising a pair of spaced, parallel transmission lines 55, 55, terminated in their surge impedance 56. Transmission line 55, 55, may have the same general construction and electrical properties as the corresponding elements described above in connection with unit 20. A plurality of pairs of adjustable taps are associated with transmission line 55, 55, three such pairs 51, 51', 58, 58' and 59, 59' being represented in the drawings. Taps 51, 58 and 59 are individually included in circuit with isolating resistors 60, 61 and 62, respectively, and a common impedance 63. Taps 51', 58' and 59' are similarly included in circuit with isolating resistors 60', 61' and 62' and a common impedance 63'. A phase inverter 64, such as a triode amplifier with unity gain, is coupled across impedance 63 and the signal derived from its output terminals 65, 65 is combined with the signal developed across impedance 63' and applied to output terminals 52, 52 of unit 20'. The impedance relations of the isolating resistors and common load impedance of this unit are substantially as described above in the discussion of unit 20.

In considering the operation of the coding arrangement of Fig. 4, reference is made to the series of curves of Fig. 5 wherein the subscripts indicate the elements of unit 20' from which the represented signal voltages are derived. It will be assumed that all of the taps illustrated in Fig. 4 are effective, and that the interrogating signal applied to input terminals 32, 32, from the amplitude limiter 13 has a wave form as represented by curve e_{32} . This signal has a maximum amplitude limited to predetermined value e , pulse-type amplitude variations of unequal pulse durations designated t_1 , t_2 and t_3 and occurring in a predetermined time sequence represented by unequal pulse spacings t_{10} and t_{11} . This interrogating signal, after being differentiated in unit 53, is applied to input terminals 54, 54, of the transversal time-delay filter network with a wave form as represented by curve e_{57} . A first plurality of signal voltages are derived at taps 51, 58 and 59 of the delay network, as shown, respectively, by curves e_{57} , e_{58} and e_{59} . This plurality of signals individually has a predetermined maximum amplitude equal to the value e if line 55 is assumed to have zero attenuation and amplitude variations or impulses determined by both the leading and trailing edges of the pulse-type amplitude variations of the received interrogating signal. The time-delay characteristics of the network and the selected relative positions of taps 51, 58 and 59, however, cause the signals to have a time relation with reference to each other such that predetermined amplitude variations or impulses of the several signals appear substantially in time-phase relation. More particularly, the relative positions of taps 51, 58 and 59 are so

chosen that the signal impulses derived from the trailing edges of the first, second, and third amplitude variations of the applied interrogating signal as derived at taps 59, 58 and 51, respectively, occur in time-phase or coincident relation. This plurality of signals develops a signal voltage across impedance 63, which is translated to phase inverter 64 appearing at output terminals 65 thereof as represented by curve e_{65} .

A second plurality of signals is derived at taps 51', 58' and 59' of the delay network. The individual signals of this second plurality of signals likewise have a predetermined maximum amplitude equal to value e and contain amplitude variations or impulses determined by the leading and trailing edges of the pulse variations of the interrogating signal. Their time relations, due to the effect of the delay filter and the relative positions of taps 51', 58' and 59', is such that the signal impulses derived from the leading edges of the first, second and third amplitude variations of the interrogating signal as obtained, respectively, at taps 59', 58' and 51' appear substantially in time-phase or coincident relation. The signal of curve $e_{63'}$ is produced by this second plurality of signals across common impedance 63'. The series of taps 51', 58' and 59' are further adjusted with reference to the series of taps 51, 58 and 59 so that the in-phase or coincident impulses of the second plurality of signals occur in the same time-phase relation as the in-phase or coincident impulses of the first plurality of signals. This phase relationship will be clear from a comparison of curves $e_{63'}$ and e_{65} . As a consequence, the output signal obtained at output terminals 52, 52 of the network, resulting from the combination of the signals represented by curves $e_{63'}$ and e_{65} , has the wave form of curve e_{52} . By adjusting the clipping level of clipping amplifier 14 to a value indicated by a broken-line curve c' , a single control effect is derived from this output signal for keying multivibrator 15. Thus, the improved coding arrangement of Fig. 4 is critical not only to the time sequence of the amplitude variations of the received interrogating signal, but also to the pulse durations of such amplitude variations.

A modification of the coding arrangement for the transmitter portion of the transponder system is represented in Fig. 6 and indicated generally as 40'. This arrangement is similar in construction and design to unit 40, described above, and corresponding components thereof are designated by like reference numerals primed. However, unit 40' includes a second series of adjustable taps 45'', 46'' and 47'' as well as isolating resistors 49'', 49'', and 50'' and a common impedance 51''. The input circuit of a phase inverter 70 is coupled across impedance 51'' and the signal derived in the output circuit thereof is applied to the input terminals of an integrating circuit 71 along with the signal voltage developed across common impedance 51''. The integrating circuit may be of the type shown at page 163, Fig. 95 of "Principles of Television Engineering," supra. The output terminals 42', 42', of unit 40' are coupled to the output terminals of integrating circuit 71.

To utilize the described modification of the coding arrangement in the transponder system of Fig. 1, multivibrator 15 is adjusted to generate a sharp pulse of rectangular wave form having a pulse duration t_{15} , curve f of Fig. 7. This curve demonstrates the time relation of the pulses derived at the individual taps of the transversal

time-delay filter network in response to a single pulse applied from multivibrator 15. Phase inverter 19, by inverting the phase of the signals developed at taps 45'', 46'' and 47'', causes the signal delivered to integrating circuit 11 to have a wave form as represented by curve g. It will be noted that this signal effectively comprises a plurality of pairs of signals appearing in a predetermined time sequence and individually comprising unidirectional signals of opposite polarities having a predetermined time separation. That is, for the assumed relative positions of the adjustable taps, the derived pairs of signals have individual time separations indicated t_{16} , t_{17} and t_{18} and appear in a time sequence represented by intervals t_{19} and t_{20} . The integrated signal obtained at output terminals 42', 42'', has a wave form as indicated by curve h and, after translation through amplifier 16, controls wave-signal generator and modulator 17 to transmit a reply signal having a modulation envelope of similar wave form. Thus, unit 40' permits the coded reply signal to have components of predetermined pulse duration and pulse spacings as determined by the selective positioning of the adjustable taps associated with transmission line 43', 43''.

The described coding arrangements are extremely flexible and provide a degree of secrecy which increases with the complexities of the particular arrangement utilized. By increasing the number of taps utilized in unit 20, for example, the receiver may be selectively responsive to an interrogating signal containing spaced groups of many more than three amplitude variations appearing within each group in a predetermined time sequence. The receiver arrangement may be further modified to provide a higher degree of secrecy by utilizing an increased number of pairs of taps in the manner described in connection with the arrangement of Fig. 4 so that the receiver is responsive to the duration as well as the spacings, or time sequence, of the amplitude variations of the interrogating signal. In like manner, the secrecy features of the transmitter portion may be varied by including any desired number of taps or pairs of taps in the coding arrangement of units 40 and 40', respectively, spaced in accordance with any desired coding schedule.

Although it is preferred that coding arrangements be associated with both the receiver and transmitter portions of the transponder system, either one may be omitted. Where the coding feature is utilized in the transmitter but omitted from the receiver, a complete coded answer is transmitted in response to a single pulse modulation of the interrogating signal.

In any case, where coding of the transmitted reply signal is employed, it is desirable to provide a holding or blocking feature in the receiver to disable the receiver for such a period of time following the tripping of multivibrator 15 that a complete coded reply may be transmitted before an interrogating signal is able to trip the multivibrator a second time. In many applications this feature will be inherent in the receiver since the transmitted signal, which is intercepted by the receiving antenna system 10, 11, in most installations will have such power as to overload the receiver circuits and disable the receiver for a period of time determined by its inherent time constant. Alternatively, the time-constant circuits of multivibrator 15 may be adjusted to provide this blocking feature.

The described transversal time-delay filter networks are especially useful in the coding arrangements under consideration since they permit the coding schedules to be altered through the simple expedient of adjusting the number or relative positions of the adjustable taps. The maximum time delay desired to be obtained in the network governs the lengths of the transmission lines of the described networks.

- 10 In the foregoing explanation of the invention, the interrogating signal has been assumed to have amplitude variations appearing in a predetermined sequence. The invention is equally applicable to transponder systems designed to receive interrogating signals having pulse-type frequency or phase variations appearing in a predetermined time sequence. Therefore, the expression "an interrogating signal having predetermined characteristic variations appearing in a predetermined time sequence," as used in the description and the appended claims, is intended to include all such applications.

It will be apparent from the described operation of units 20 and 20' and particularly from the curves of Figs. 2 and 5, that the amplitude-limiting feature of a transponder system including a coded receiver in accordance with the invention results in an improved signal-to-noise ratio. This feature results from the fact that noise signals being of a random nature will, in general, fall below the clipping level of amplifier 14, and thus be ineffective to cause a response from the system.

It will be understood that multivibrator 15 is a desired, but not absolutely necessary component of the transponder system. By including this component in the system, the pulse-type characteristic variations of the transmitted reply signal may have any desired pulse durations, even though the coding arrangement of Fig. 6 be omitted. Otherwise, installations which lack transmitter coding facilities similar to that of Fig. 6 transmit answer signals having characteristic variations of pulse durations substantially the same as that of the interrogating signal.

While there have been described what are at present considered to be the preferred embodiments of this invention, it will be obvious to those skilled in the art that various changes and modifications may be made therein without departing from the invention, and it is, therefore, desired in the appended claims to cover all such changes and modifications as fall within the true spirit and scope of the invention.

55 What is claimed is:

1. In a wave-signal transponder system for utilizing an interrogating signal having a plurality of pulse-type characteristic variations of predetermined pulse durations occurring in a predetermined time sequence, a selective receiving system comprising, time-delay means, means associated with said time-delay means for deriving from said interrogating signal a first corresponding plurality of signal impulses limited to a predetermined maximum amplitude, occurring in time coincidence and individually representing the leading edge of a different predetermined one of said pulse-type characteristic variations of said interrogating signal, means also associated with said time-delay means for deriving from said interrogating signal a second corresponding plurality of signal impulses limited to a predetermined maximum amplitude, occurring in time coincidence with one another and with said first plurality of impulses and individually representing the trail-

ing edge of a different predetermined one of said pulse-type characteristic variations of said interrogating signal, and amplitude-selective means unresponsive to signal impulses of said predetermined maximum amplitudes but responsive jointly to said coincident first and second plurality of signal impulses for deriving an output signal from said receiving system, whereby said receiving system is responsive only to interrogating signals having a plurality of pulse-type characteristic variations of said predetermined pulse durations occurring in said predetermined time sequence.

2. A selective wave-signal translating system for translating a signal having a plurality of pulse-type amplitude variations of predetermined pulse durations occurring in a predetermined time sequence comprising, an input circuit for receiving said signal, means coupled to said input circuit for deriving from said received signal a first corresponding plurality of signal impulses occurring in time coincidence and individually representing the leading edge of a different one of said pulse-type amplitude variations of said received signal, means for deriving from said received signal a second corresponding plurality of signal impulses occurring in time coincidence with one another and with said first plurality of signal impulses and individually representing the trailing edge of a different one of said pulse-type amplitude variations of said received signal, and means responsive jointly to said coincident first and second plurality of signal impulses for deriving an output signal, whereby said translating system is responsive only to signals having pulse-type amplitude variations of said predetermined pulse durations occurring in said predetermined time sequence.

3. A selective wave-signal translating system for translating a signal having a plurality of pulse-type amplitude variations of predetermined pulse durations occurring in a predetermined time sequence comprising, an input circuit for receiving said signal, means coupled to said input circuit for deriving from said received signal a first corresponding plurality of signal impulses limited to a predetermined maximum amplitude, occurring in time coincidence and individually representing the leading edge of a different one of said pulse-type amplitude variations of said received signal, means for deriving from said received signal a second corresponding plurality of signal impulses limited to a predetermined maximum amplitude, occurring in time coincidence with one another and with said first plurality of signal impulses and individually representing the trailing edge of a different one of said pulse-type amplitude variations of said received signal, and means unresponsive to signal impulses of said predetermined maximum amplitudes but responsive jointly to said coincident first and second plurality of signal impulses for deriving an output signal, whereby said translating system is responsive only to signals having pulse-type amplitude variations of said predetermined pulse durations occurring in said predetermined time sequence.

4. A selective wave-signal translating system for translating a signal having a plurality of pulse-type amplitude variations of predetermined pulse durations occurring in a predetermined time sequence comprising, an input circuit for receiving said signal, means for applying said signal to said input circuit with a maximum amplitude limited to a predetermined value, means coupled to said input circuit for deriving from said received signal a first corresponding plural-

ity of signal impulses limited to said predetermined maximum amplitude, occurring in time coincidence and individually representing the leading edge of a different one of said pulse-type amplitude variations of said received signal, means for deriving from said received signal a second corresponding plurality of signal impulses limited to said predetermined maximum amplitude, occurring in time coincidence with one another and with said first plurality of signal impulses and individually representing the trailing edge of a different one of said pulse-type amplitude variations of said received signal, and means unresponsive to signal impulses of said predetermined maximum amplitude but responsive jointly to said coincident first and second plurality of signal impulses for deriving an output signal, whereby said translating system is responsive only to signals having pulse-type amplitude variations of said predetermined pulse durations occurring in said predetermined time sequence.

5. A selective wave-signal translating system for translating a signal having a plurality of pulse-type amplitude variations of predetermined pulse durations occurring in a predetermined time sequence comprising, means including a time-delay network for receiving said signal, means coupled to said time-delay network for deriving from said received signal a first corresponding plurality of signal impulses occurring in time coincidence and individually representing the leading edge of a different one of said pulse-type amplitude variations of said received signal, means also coupled to said time-delay network for deriving from said received signal a second corresponding plurality of signal impulses occurring in time coincidence with one another and with said first plurality of signal impulses and individually representing the trailing edge of a different one of said pulse-type amplitude variations of said received signal, and means responsive jointly to said coincident first and second plurality of signal impulses for deriving an output signal, whereby said translating system is responsive only to signals having pulse-type amplitude variations of said predetermined pulse durations occurring in said predetermined time sequence.

6. A selective wave-signal translating system for translating a signal having a plurality of pulse-type amplitude variations of predetermined pulse durations occurring in a predetermined time sequence comprising, means including a differentiating circuit and a serially connected time-delay network for receiving said signal, means coupled to said time-delay network for deriving from said received signal a first corresponding plurality of signal impulses occurring in time coincidence and individually representing the leading edge of a different one of said pulse-type amplitude variations of said received signal, means also coupled to said time-delay network for deriving from said received signal a second corresponding plurality of signal impulses occurring in time coincidence with one another and with said first plurality of signal impulses and individually representing the trailing edge of a different one of said pulse-type amplitude variations of said received signal, and means responsive jointly to said coincident first and second plurality of signal impulses for deriving an output signal, whereby said translating system is responsive only to signals having pulse-type amplitude variations of said predetermined pulse durations occurring in said predetermined time sequence.

pulse durations occurring in said predetermined time sequence.

7. A selective wave-signal translating system for translating a signal having a plurality of pulse-type amplitude variations of predetermined pulse durations occurring in a predetermined time sequence comprising, means including a differentiating circuit and a serially connected time-delay network for receiving said signal, a first series of taps associated with said time-delay network for deriving from said received signal a first corresponding plurality of signal impulses occurring in time coincidence and individually representing the leading edge of a different one of said pulse-type amplitude variations of said received signal, a second series of taps also associated with said time-delay network for deriving from said received signal a second corresponding plurality of signal impulses occurring in time coincidence with one another and with said first plurality of signal impulses and individually representing the trailing edge of a different one of said pulse-type amplitude variations of said received signal, and means responsive jointly to said coincident first and second plurality of signal impulses for deriving an output signal, whereby said translating system is responsive only to signals having pulse-type amplitude variations of said predetermined pulse
